(57) **CLAIM**

The ornamental design for a diagnostic instrument for a vehicle, as shown and described.

DESCRIPTION

FIG. 1 is a front view of a diagnostic instrument for a vehicle, showing my new design;

FIG. 2 is a top plan view thereof;

FIG. 3 is a bottom plan view thereof;

FIG. 4 is a rear plan view thereof;

FIG. 5 is a left plan view thereof;

FIG. 6 is a right plan view thereof; and,

FIG. 7 is a perspective view thereof.

The broken lines are shown for the purpose of illustrating portions of the diagnostic instrument for a vehicle and forms no part of the claimed design.

1 Claim, 7 Drawing Sheets
